UNITED STATES PATENT OFFICE.

PIERRE DE LA BASTIDE, OF LIMOGES, FRANCE.

DESIGN FOR A DISH.

SPECIFICATION forming part of Design No. 22,154, dated January 24, 1893.

Application filed December 19, 1892. Serial No. 455,742. Term of patent 3½ years.

To all whom it may concern:

Be it known that I, PIERRE DE LA BASTIDE, a citizen of France, and a resident of Limoges, France, have invented a new Design for Dishes, of which the following is a specification.

In the accompanying drawings, Figure 1 is a side-view of a soup tureen and cover, embodying my design for dishes. Fig. 2 is a top-view of the cover.

Similar letters of reference indicate corresponding parts.

The leading feature of my design consists in the shape of the dishes, a flat relief surface ornamentation and leaf ornament handles. The contour of the soup tureens and like dishes, as shown in Fig. 2, consists of two end curves *a* and *a'* of different radius, an S curve *d* on one side and partial eclipse curve *e* on the other. The surface ornamenta-

tion consists of tapering flutings *f* arranged in groups, scallops *g* at the wider ends of said flutings and eyes *h* in the wider ends of the flutings and of flat relief arabesque leaves *k*, said flutings and arabesque leaves alternating on different parts of the dishes. The handles *m* have ornaments *o* and *p*.

Having thus described my invention, what I claim as new and desire to secure by Letters Patent is:—

The design for dishes, substantially as herein shown and described.

In testimony that I claim the foregoing as my invention I have signed my name in presence of two subscribing witnesses.

P. DE LA BASTIDE. [L. S.]
